UNITED STATES PATENT OFFICE

105,086

DESIGN FOR A SECTIONAL DISPLAY STAND

Robert Bradshaw, Phoebus, Va.

Application April 21, 1937, Serial No. 68,917

Term of patent 7 years

To all whom it may concern:

Be it known that I, Robert Bradshaw, a citizen of the United States, residing at Phoebus, in the county of Elizabeth City and State of Virginia, have invented a new, original, and ornamental Design for a Sectional Display Stand, of which the following is a specification, reference being had to the accompanying drawing, forming part thereof.

Figure 1 is an elevational view of the sectional display stand, showing my new design;

Figure 2 is a top plan view;

Figure 3 is a bottom plan view; and

Figure 4 is a perspective view thereof.

I claim:

The ornamental design for a sectional display stand as shown.

ROBERT BRADSHAW.
